GAME RACEWAY

George W. Dunbar, Nashville, Tenn., assignor to Kusan, Inc., Nashville, Tenn.

Filed Oct. 4, 1963, Ser. No. 76,872

Term of patent 7 years

(Cl. D34—15)

FIG-1

FIG-2

FIG-3

FIG-4

5

FIG-5

5

I claim:

The ornamental design for a game raceway, as shown.
